US0D1041025S

(12) **United States Design Patent** (10) Patent No.: **US D1,041,025 S**
(45) Date of Patent: ** Sep. 3, 2024

(54) **TEST CARD**

(71) Applicant: **Zhejiang Orient Gene Biotech Co., Ltd**, Zhejiang (CN)

(72) Inventors: **Jianqiu Fang**, Zhejiang (CN); **Siyu Lei**, Zhejiang (CN); **Hua Zhang**, Zhejiang (CN)

(73) Assignee: **ZHEJIANG ORIENT GENE BIOTECH CO., LTD**, Zhejiang (CN)

(**) Term: **15 Years**

(21) Appl. No.: **29/930,513**

(22) Filed: **Feb. 29, 2024**

Related U.S. Application Data

(62) Division of application No. 29/860,937, filed on Nov. 23, 2022.

(30) **Foreign Application Priority Data**
